UNITED STATES PATENT OFFICE.

EDWARD W. HART, OF OMAHA, NEBRASKA, ASSIGNOR TO MORRIS CASH AND CREDIT REGISTER COMPANY, OF OMAHA, NEBRASKA, A CORPORATION OF MAINE.

AUTOMATIC REVERSING MECHANISM FOR INK-RIBBONS.

1,363,509.

Specification of Letters Patent. Patented Dec. 28, 1920.

Application filed December 9, 1918. Serial No. 265,825.

To all whom it may concern:

Be it known that I, EDWARD W. HART, a citizen of the United States, and a resident of Omaha, in the county of Douglas and 5 State of Nebraska, have invented certain new and useful Improvements in Automatic Reversing Mechanism for Ink-Ribbons; and I do hereby declare that the following is a full, clear, and exact description thereof, 10 reference being had to the accompanying drawings, and to the letters of reference marked thereon, which form a part of this application.

In the drawings:

15 Fig. 1 illustrates in side elevation, the actuating mechanism of a cash register, embodying my improved ribbon reversing mechanism.

20 Fig. 2 illustrates, on an enlarged scale, a side elevation of parts of the automatic reversing mechanism and shows said parts in changed position from that shown in Fig. 1.

25 Fig. 3 illustrates a vertical section through parts of the mechanism shown in Fig. 1, the plane of the section being indicated by the line 3—3 of Fig. 1.

30 Fig. 4 illustrates a horizontal plan sectional view of parts shown in Fig. 3, the plane of the section being indicated by the line 4—4 of Fig. 3.

35 Fig. 5 illustrates a vertical section through parts of the cash register mechanism, to which my invention has been applied, and shows the relative location of the two ribbon spool shafts, the plane of the section being indicated by the line 5—5 of Fig. 3.

40 Fig. 6 illustrates a view similar to that shown in Fig. 3, but with the parts shown in changed relation.

Fig. 7 illustrates a detail vertical section through parts of the automatic reversing mechanism, the plane of the section being indicated by the line 7—7 of Fig. 6.

45 Figs. 8 and 9 are views in elevation of parts of the reversing mechanism which will be more specifically referred to later.

50 This invention relates to improvements in automatic reversing mechanism for ink ribbon wind and rewind spools and consists of the matters hereinafter described and more particularly pointed out in the appended claims.

55 The object of the invention is to provide an efficient, simple and automatic means for

reversing the feed of an ink ribbon from one spool to the other spool, so that, as when unwinding from the first spool and winding upon the second spool, the end is approached on the first spool, said spool will 60 begin to rewind the ribbon, which will then be unwound from the second spool, and vice versa.

The invention is herein illustrated and described as used in connection with the mechanism of a cash register of the type shown in the patent to J. L. Morris and A. W. Larimore, No. 1,292,354 of Jan. 21, 1919, but as is apparent, the invention may be incorporated in other machines where its peculiar characteristics make it advantageous to do so.

Referring now in detail to that embodiment of the invention illustrated in the accompanying drawings:—10 indicates one of 70 a pair of upright side frame members of the cash register mechanism, and 11 indicates a cover plate which is pivoted at its ends to the said frame members by screws 12, so as to swing in a vertical plane.

75 13 and 14 indicate respectively the rear and front ribbon spool shafts respectively. The rear spool shaft is journaled in bearings 15 carried by the cover plate 11 (see Fig. 5), while the front ribbon spool shaft is 80 journaled at its ends in the side frame members 10. Fixed to one end of the shaft 14, beyond the frame 10, is a ratchet wheel 16, and fixed to the corresponding end of the shaft 13 within the frame 10, is a pinion 17 85 (see Fig. 2), which, when the cover plate is in its closed position, as shown in Figs. 1 and 5, normally meshes with a pinion 18 on the inner end of a stub shaft 19 journaled in the side frame members 10. Said stub shaft projects beyond the frame member 10, where it has a ratchet wheel 16^a which, like the ratchet 16, is rotated step by step in a manner soon to appear.

90 Fixed on the shafts 13 and 14, are a plurality of ribbon spools 13^a and 14^a respectively arranged in pairs in tandem, and a transfer or ink ribbon 20 associated with each pair of spools 13^a and 14^a. The ribbon 20 from one spool 13^a, passes through slots 135 20^a in the cover plate, over and above the platen bar 21 and then to the other spool 14^a associated therewith.

95 A record strip 22, fed from a supply roll 23, passes over the platen beneath the rib- 110

bon 20, to be wound upon a record rewind roll 24. A check strip 25 is associated with each ribbon and passes through the cover plate 11 above the ribbon 20, there being 5 suitable openings in the cover plate, above the platen bar to expose the check strip to view, so that it may be written upon, said 10 ribbon transferring the inscription to the record strip. The record strip is fed in proper manner by a lever plate 26 on the cover plate, which lever has a pawl to engage with an arm 27 to actuate a feed roll 28 associated with each record strip. All 15 of the arms 27 extend through and are suitably supported by a bar 29 which is fixed at its ends to the side frame members 10, 10 in a plane vertically above the front ribbon roll shaft 14.

30 indicates a lever which is pivoted at 20 31 to the frame member 10, at a point between and below the shafts 14 and 19, so as to swing or rock in a plane parallel to said frame member. This lever has two oppositely disposed, relatively long and short 25 pawls 32, 33 pivoted to its top end. The long pawl 32 is associated with the ratchet 16^a on the stub shaft 19 while the short pawl 33 is associated with the ratchet 16 on the ribbon shaft 14. A spring 34 carried by the lever 30 near its top end, normally tends to hold both pawls in engagement with their associated ratchet wheels.

35 indicates a bifurcated plate which is pivoted on a screw 36 in the frame member 10, in a plane vertically above the pivot 31 of the lever 30. This plate which is capable of a rocking movement upon the screw 36, includes oppositely disposed, depending legs 37 and 38, one associated with 40 each pawl 32 and 33 respectively, and substantially long and short, upwardly disposed arms 39 and 40 respectively. Each arm carries a yielding locking dog 39^a and 40^a respectively, one associated with each 45 ratchet wheel 16 and 16^a. Normally, the parts are so arranged that when the leg 37 is out of engagement with the pawl 32, the spring 34 holds said pawl in engagement with the ratchet 16^a and the leg 38 50 will engage the pawl 33 to hold it out of engagement with the ratchet 16. When the pawl 32 engages the ratchet 16^a, the locking dog 40^a also engages the said ratchet and the locking dog 39^a is out of 55 engagement with the pawl 16, as shown in Fig. 1.

With the parts in the position just described, and when the lever 30 is actuated, as will be presently described, the pawl 32 60 will actuate the ratchet 16^a to wind up the ribbons on the spools 13^a, the ribbons unwinding from the spools 14^a. When the bifurcated plate 35 is rocked, as will presently appear, into the position shown in Fig. 2, the leg 37 will hold the pawl 32 out

of engagement with the ratchet 16^a and will permit the pawl 33 to engage the ratchet 16. When the parts are in this position and the lever 30 is actuated, the ribbon spools 14^a will act as rewind spools, 70 the ribbons then unwinding from the spools 13.

The lever 30 is actuated as follows:—42 indicates the master operating lever of the cash register mechanism, which lever is pivoted at 43 to the frame member 10. This lever includes a short arm 44 at its bottom end which is connected by a link 45 with an arm 46, pivoted to the rear end of the frame as at 47. Said arm 47 is operatively 80 connected to a pawl 48 which engages a ratchet 49 on the end of the record rewind roll 24, to wind up the record strip 22. In the link 45 is a pin 45^a which engages the forked bottom end 30^a of the lever 30. 85 When the master lever 42 is actuated, the short arm 44 will cause a rearward movement of the link 45 by reason of the connection between said link and the lever 30, and the top end of said lever will swing 90 forwardly and cause that pawl 32 or 33 in engagement with its associated ratchet, to feed said pawl to wind up the ribbons on the spools of the associated shaft. Also said movement of the master lever will, through 95 the link 45, arm 46 and pawl 48, cause the record rewind roll 24 to be actuated to wind up the record strip thereon. When the master lever 42 is released, it will return the several parts to the initial position, 100 ready to operate upon the next movement of said master lever.

When, in the unwinding movement, the ends of the ribbons on the spools are being approached, a suitable means is automatically actuated to rock the bifurcated plate 35, so as to disengage that pawl from its ratchet which is operatively connected to the rewind shaft and the spools thereon, and permit the other pawl to engage its associated ratchet so that the spools which in the first instance acted as the supply spools, will now be the rewind spools, and the ribbons will be wound upon said spools from the other spools, which will then become the 115 ribbon supply spools. This means is as follows:

That part of the ribbon spool shaft 14 between the end frame member 10 and the first adjacent spool 14^a, is screw threaded 120 and on said shaft and having a screw threaded engagement therewith, is a sleeve 50 which travels endwise of said shaft in the rotation of said shaft, (see Figs. 3, 4 and 6) according to the direction in which said 125 shaft rotates. This sleeve carries a horizontally extending stud 51 in the form of a set screw which projects through an enlarged hole 52 in the bottom end of a swinging lever 53. Said lever (shown in detail in Fig. 9) 130

is pivoted at its top end on a screw 54 secured in the bar 29 before mentioned, and has a part in its middle which is punched and bent out to provide a rearward extension 55. In said extension is a vertically arranged hole 55^a (see Fig. 7), through which extends the bottom end of a swinging arm 56 that is pivoted on a screw 56^a carried by a plate 57 (shown in detail in Fig. 8) that 10 is movably mounted on the bar 29. An expansion coiled spring 56^b surrounds said arm between the extension 55 and the enlarged head of said arm.

The plate 57 is held in position upon the 15 bar 29 by means of screws 58 which extend through slots 59 in said plate, said slots and screws permitting of a guided, laterally shifting movement of said plate upon the bar 29. Said plate is also provided between 20 the slots 59 with another slot 60 through which the pivot of the lever 53 extends. That end of said plate near the frame member 10 has a depending, forked extension 61 which engages with the shorter arm 62 of a 25 bell crank lever 63 (see Figs. 3, 4 and 6). This lever is pivoted to a bracket 64 at the end of the bar 29, so as to swing or rock in a horizontal plane, and the longer arm 64 of said lever is extended through a hole 66 in 30 the end frame 10. Said long arm 65 is connected by a link 67 to a rearward extension 68 rigidly fixed to the top end of the long arm 39 of the bifurcated lever plate 35.

The operation of the reversing mechanism 35 is as follows: When the parts are in the position shown in Figs. 2 and 3, the spools 14^a on the ribbon shaft 14 will act as the rewind spools to take off and wind up the ribbons from the spools 13^a on the shaft 13. 40 In each movement of the master lever 42, to actuate the cash register mechanism, the top end of the lever 30 is caused to swing forwardly, the pawl 33 imparting a short rotative movement to the ratchet 16 and ribbon spool shaft 14. The dog 39^a prevents 45 backward movement of the ratchet when the pawl 33 is disengaged from the said ratchet in the return movement of the master lever 42. As this shaft 14 is thus rotated step by step, it will draw the ribbon from the spools 13^a, the shaft 13 and its associated ratchet 16 being free from engagement with the 50 associated pawl 32 and dog 40^a.

As this rotative movement is imparted to 55 the shaft 14, the sleeve 50 thereon will travel endwise on said shaft from the position shown in Fig. 3 toward the end frame member 10, into the position shown in Fig. 6. In its endwise traveling movement, said 60 sleeve will, through the stud 51, swing the lever 53 slowly toward the right, as shown in Fig. 3. In this swinging movement, the arm 56 is also caused to swing, the spring 58 being compressed by reason of the shortening up of the distance between the pivot

56^a and the extension 55 on the lever 53. When the center line of the lever 53 swings through and beyond the plane of a line passing through the axis of the pivots 54 and 56^a, the said spring will tend to again expand. This expansion of the spring will 70 exert an upward movement to the lever 56 and as said lever is pivoted to the movable plate 57, and as said plate is so guided that it can only move laterally or endwise, a 75 quick lateral shift or movement of said plate will take place.

This movement of the plate (away from the frame 10, as shown in Fig. 6) will, through the depending fork extension 61, 80 impart a swinging movement to the bell crank 63. Said bell crank will, through the link 67, rock the bifurcated lever 35 so that the leg 37 is disengaged from the pawl 32, which will engage its associated ratchet 16^a 85 and the leg 38 will engage the pawl 33 and remove it from operative engagement with the ratchet 16. In this rocking movement of the bifurcated lever 35, the dog 39^a is withdrawn from ratchet 16 and the dog 40^a 90 will engage the ratchet 16^a. The parts are shown in this last mentioned position in Fig. 1.

In the further operation of the master lever 42, the rocking lever 30 will cause the 95 pawl 32 to pull upon the ratchet 16^a to impart a short, rotative movement to it, which movement will be transmitted to the ribbon shaft 13 through the gears 18 and 17. The shaft 13 will be rotated step by 100 105 110 115 120 125 130 135 140 145 150 155 160 165 170 175 180 185 190 195 200 205 210 215 220 225 230 235 240 245 250 255 260 265 270 275 280 285 290 295 300 position wherein it will move the lever 53 to actuate the arm 56 to shift the plate 57, which in turn will change the feed from one set of spools to the other.

5 It is apparent that my improved ribbon reversing mechanism has many advantages. It positively and automatically shifts the feed of the ribbon from one set of spools to the other, when the ends of said ribbon are 10 approached, and therefore there is no danger of stripping the ribbons from the spools.

Said reversing means comprises but few parts which are easily assembled and which cannot get out of order.

15 While in describing my invention, I have referred to certain details of mechanical construction and arrangement of parts, and have referred to the same as being used in connection with a cash register mechanism, 20 I do not wish to be limited thereto except as may be pointed out in the appended claims.

I claim as my invention:

1. An automatic reversing mechanism for 25 ink ribbons comprising in combination, two ribbon spool shafts, a ribbon spool on each shaft, a ratchet wheel operatively connected to each shaft, a pawl associated with each ratchet wheel to impart a step by step, 30 rotative movement thereto, a lever plate for alternately holding one of said pawls out of engagement with its associated ratchet wheel and at the same time permitting the other device to engage with its associated ratchet wheel, a sleeve movable endwise on 35 one of said shafts in the rotation of said shaft, a support, a lever pivoted on said support and operatively connected to said sleeve and adapted to be swung thereby, a plate movable on said support and operatively 40 connected to said lever plate, and means between said swinging lever and said plate to shift said plate to actuate said lever plate upon the approach of the end of the ribbon on either of said shafts.

45 2. An automatic reversing mechanism for ink ribbons comprising in combination, two ribbon spool shafts, a ribbon spool on each shaft, a ratchet wheel operatively connected to each shaft, a pawl associated with each

ratchet wheel to impart a step by step, rotative movement thereto, a lever plate for alternately holding one of said pawls out of engagement with its associated ratchet wheel and at the same time permitting the other device to engage with its associated 50 ratchet wheel, a sleeve movable endwise on one of said shafts in the rotation of said shaft, a support, a lever pivoted on said support and operatively connected to said sleeve and to be swung thereby, a plate movable 55 on said support and operatively connected to said lever, and a spring actuated device between said swinging lever and said plate to shift said plate to actuate said lever plate upon the approach of the end of the ribbon 60 on either of said shafts.

3. An automatic reversing mechanism for ink ribbons comprising in combination, an upright frame member, two horizontal ribbon spool shafts, a ribbon spool on each 70 shaft, a ratchet wheel operatively connected to each shaft without the frame member, a swinging lever on said frame member, pawls carried by said lever, one associated with each ratchet wheel to impart a step by step 75 rotative movement thereto, a lever plate also pivoted on said frame members for alternately holding one of said pawls out of engagement with its associated ratchet wheel and at the same time permitting the 80 other pawl to engage with its associated ratchet wheel, ratchet holding dogs on said lever plate, a sleeve movable endwise on one of said spool shafts in the rotation thereof, and means operable by said sleeve as it approaches the limit of its endwise movement 85 on said shaft to shift said lever plate, said means including parts extending through said frame member.

In testimony, that I claim the foregoing 90 as my invention, I affix my signature in the presence of two witnesses, this 5th day of December, A. D. 1918.

EDWARD W. HART.
